UNITED STATES PATENT OFFICE.

JOHN P. FOLEY, OF GALESBURG, ILLINOIS.

CASKET-HANDLE.

1,312,171.

Specification of Letters Patent. Patented Aug. 5, 1919.

Application filed April 22, 1918. Serial No. 230,034.

To all whom it may concern:

Be it known that I, JOHN P. FOLEY, a citizen of the United States, and a resident of Galesburg, in the county of Knox 5 and State of Illinois, have invented a new and useful Casket-Handle, of which the following is a specification.

My present invention relates to casket-handles of that general type or class disclosed in United States Letters Patent No. 10 1,202,987, granted to me October 31, 1916, on which the device herein shown and described is an improvement.

The principal object of the invention is to provide certain improvements in the inter-engaging portions of the escutcheon-plate and the hanger-arms, whereby a much stronger and more rigid handle is produced.

In the accompanying drawings: 20 Figure 1 is a front elevation, showing the escutcheon-plate, one of the connecting or hanger-arms in position and the other omitted, and a fragment of the handle-bar;

25 Fig. 2, a perspective of one end portion of one of the hanger-arms;

Fig. 3, a section, partly in elevation, its plane taken in the line 3—3 in Fig. 1; and

Fig. 4, a detail section, taken in the plane of the line 4—4 in Fig. 1.

30 Considering the drawings in detail, 2 designates an escutcheon-plate, preferably formed from sheet metal, the one shown being of a well known general outline. It is provided with openings 3 into each of 35 which project gudgeons 6, faced toward each other and acting as fulcrums on which the hanger-arms are hinged. At the upper edge of each opening 3 is a bearing tongue 7 concavo-convex in cross section. In these 40 tongues reside one of the main features of my improvements, namely: The escutcheon plates are made of relatively thin sheet metal. A great amount of weight has to be resisted by each tongue. It is impractical, 45 owing to the nature of the article and the demand that it be ornamental and pleasing to the eye, to make the tongues of any considerable size. The problem, then, was to strengthen the tongue (which in itself is 50 not new) without increasing its size, and I discovered that by giving it the arciform shape shown best in Figs. 1 and 4 that this object would be obtained. In order to add still greater strength I continue or extend 55 the fullness or arc-shape into the body of

the plate, as shown best at 8, Figs. 1 and 4, where it tapers off to a point.

The hanger arms 4 also are formed of relatively thin sheet metal and may be of any preferred general structure, my improvement therein residing in providing the inner ends of each thereof with a channel 60 9 terminating in a shoulder 10. 11, 11 designate registering openings in which the gudgeons 6 are fulcrumed. 12 designates 65 the usual handle-bar.

Fig. 3 shows the device in operative position, as in carrying a casket, the hanger-arms 4 fulcruming on the gudgeons 6 and the terminals of the tongues 7 bearing on 70 the shoulders 10. (It is to be observed that in moving the hanger-arms upward or downward the tongues will move in the channels 9 and that, therefore, the plating or other finishing will not be marred.) Be- 75 cause of the hereinabove described novel structural peculiarities of the tongues 7 and their extensions 8 a very much greater weight will be resisted thereby, without their yielding or giving way, than is the 80 case in any former device now known to me. The shoulder 10 being formed without slitting or otherwise cutting the metal, of course offers sufficient resistance against any weight which may be placed upon it. 85

I realize that some variation is possible in the details of this construction without departing from the spirit of the invention; therefore I do not intend to limit myself to the specific form herein shown and de- 90 scribed except as pointed out in the following claims, in which it is my intention to claim as broadly as is permitted by the state of the art all the novelty inherent in 95 the invention.

Having thus described the nature of the invention I claim as new:

1. In a device of the class described, an escutcheon-plate having a hanger arm receiving aperture, the wall of the plate immediately above the central vertical portion of said aperture being formed outwardly to provide a weight resisting tongue, said tongue extending down into the aperture and rounded on its lower edge, and a 100 hanger arm hinged to said plate, and provided with a channel on its inner upper end conforming to the shape of said tongue whereby adjustment of said handle causes 105 said handle to guide on said tongue and 110

- said hanger arm having a shoulder at the end of said channel to form an abutment for contact with said tongue when said handle is in an elevated position.
- 5 2. In a device of the class described, an escutcheon-plate having a hanger arm receiving aperture, a tongue formed integrally with said plate projecting outwardly therefrom and downwardly over said aperture
- 10 and formed in a concavo-convex shape both laterally and longitudinally, a hanger arm pivotally associated with said escutcheon
- plate having a channel formed on the end thereof conforming to the contour of the said tongue whereby said channel guides on 15 said tongue for adjustment of the handle and an abutment formed on said hanger arm at the end of said channel to contact against said tongue and transmit a lifting stress applied at said handle to said escutcheon plate. 20

In testimony whereof I hereunto attach my signature this 13th day of April, 1918.

JOHN P. FOLEY.
